ROLLER SKATE

Samuel M. Allred, Dayton, Ohio

Application September 25, 1939, Serial No. 296,364

5 Claims. (CL 230—11.26)

This invention relates to a roller skate and more particularly to that type of roller skate in which the main or foot supporting frame is tiltable with relation to the trucks to enable the same to accommodate itself to the position of the skater in making turns and the like, the tilting movement of the frame being controlled by a yieldable or cushioning member. Skates of this kind as heretofore constructed have not been entirely satisfactory due in part at least to the fact that the main frame was of such a character that it did not possess the strength and rigidity necessary to resist the strains to which it is subjected in the normal use of the skate, and, further, due to the fact that the means for pivotally connecting the main frame with the trucks were liable to distortion or breakage, and, further, that their connection with the main frame were such that they tended to distort the latter under severe strains.

One object of the present invention is to provide a skate of this kind with a very simple main frame structure which will have ample strength and rigidity to resist all strains to which it may be subjected in the normal operation of the skate.

A further object of the invention is to provide a strong rigid truck frame having simple but efficient means for connecting the same with the main frame and which will be so connected with the main frame that it will not distort or otherwise injure the latter.

A further object of the invention is to provide a skate of this kind which will be simple in its construction and can be produced at a relatively low cost.

Other objects of the invention may appear as the skate is described in detail.

In the accompanying drawing Fig. 1 is a plan view, partly broken away, of a skate embodying my invention; Fig. 2 is a side elevation of such a skate, partly in section and partly broken away; and Fig. 3 is a transverse section taken on the line 3—3 of Fig. 2, showing one of the trucks in elevation.

In the drawing I have illustrated the preferred embodiment of my invention and have shown the main frame as comprising a longitudinal bar 5 extending lengthwise of the skate and, in the present instance, constituting the complete main frame structure. This main frame is provided at its ends with downwardly and inwardly extending parts 6 rigid therewith and constituting pivot members forming parts of the means for connecting the main frame with the trucks. As

here shown, these downwardly extending parts 6 are integral parts of the bar 5 and are formed by bending the end portions of that bar downwardly and inwardly as shown.

Rigidly connected with the main frame at points 5 adjacent to but spaced inwardly from the downwardly extending parts 6 are supporting members or hangers 7 having downwardly extending parts 8 forming part of the means for connecting the main frame with the truck, and here shown as provided with screw threaded sockets 9. These supporting members may be secured to the main frame or bar 5 in any suitable manner. Preferably they are provided with grooves or channels 10 to receive the bar and in which the bar may be rigidly secured in any suitable manner, as by welding. The grooves 10 are of such depth that the upper surface of the frame bar 5 will be substantially flush with the upper surfaces of the supporting members. The supporting members 7 also constitute the means for supporting the heel and toe plates of the socket and they are provided with laterally extending parts 11 which may, if desired, be of such size and shape as to constitute respectively the toe 25 and heel plates but, in the construction shown, they are in the form of apertured lugs adapted to receive and support heel and toe plates formed separately therefrom and secured thereto in any suitable manner, as by means of rivets 30 12. In the present instance, the heel plate 11a and the toe plate 11b are shown as forming parts of a one-piece foot plate but obviously they may, if desired, be formed as separate elements, and when so formed the frame bar 5 will constitute the sole connection between the front and rear parts of the skate. The frame bar 5 may be of any suitable cross sectional shape which will impart thereto the necessary strength and rigidity. In the present instance, the intermediate or horizontal portion of the bar is rectangular in cross section and the downturned end parts 6 are round in cross section, the grooves 10 of the supporting members being of rectangular shape to fit the bar.

The trucks which support the front and rear portions of the main frame are separate one from the other and are separately secured to the main frame. The two trucks are substantially identical in construction and each comprises a roller supporting frame, indicated as a whole at 13, and having an axle portion 14 which is here shown as a transverse tubular structure in which is rigidly mounted a spindle 15 which projects beyond the ends of the tubular struc- 55

ture to receive the rollers 15a, which may be mounted thereon in the usual or any suitable manner. Extending upwardly from the axle portion of the truck frame is an arm 16 which is rigidly connected with the axial portion and is preferably an integral part of the truck frame. This arm 16 is provided at its upper end with a pivot member adapted to cooperate with the adjacent pivot member or downwardly extending part 6 of the main frame. Preferably the pivot member of the arm 16 is in the form of a socket which may, if desired, be formed directly in the arm but I prefer to provide the arm with a recess 17 in which a wear resisting member 18 is rigidly mounted, as by inserting the same with a pressed fit. The socket is formed in the outer portion of the inserted member 18, as shown at 19, and is adapted to receive the end portion of the downwardly extending part 6 of the main frame. Preferably the socket is provided with a substantially semi-spherical lower or base portion 20 and the downwardly extending part 6 of the main frame is likewise provided with a substantially semi-spherical end adapted to fit in the base portion of the socket and cooperate therewith to form what is in effect a ball and socket joint, the circumferential wall of the outer portion of the socket being flared to permit the part 6 of the main frame to have rocking movement in the socket.

The truck frame is also provided with a second arm 21, rigidly connected, and preferably formed integral, therewith and extending inwardly from the axle portion 14, that is, extending toward the other truck. The arm 21 thus diverges from the arm 16 and is adapted to form a part of the connection between the truck frame and the adjacent supporting member 7. The arm 21 is provided with an opening 22 the upper portion of which is substantially annular to receive the lower end of a cushioning element, such as a block of rubber 23 having the desired degree of resiliency, and the lower portion of the opening is tapered downwardly to form a support for said cushioning member. A retaining member or cap 24 is applied to the upper end of the cushioning element and an elongate attaching member, such as a screw 25, extends through the opening in the arm 21, through the cushioning member and cap 24 and is attached to the supporting member 7, in the present instance by screwing the same into the screw threaded socket 9 of the supporting member. The attaching element or screw 25 is provided at its lower end with means for contacting the lower surface of the arm 21 about the opening 22, this means being of such a character as to limit the longitudinal movement of the screw with relation to the arm 21 but to permit the same to have pivotal movement with relation to that arm. In the present construction a washer 26 is interposed between the head of the screw and the arm 21 and is adapted to fulcrum on the lower surface of the arm when the main frame is tilted with relation to the truck. It will be obvious, however, that the arm engaging part of the screw may be an integral part of the screw. The pressure exerted upon the cushioning element 23 and therefore the resiliency of that element may be regulated by adjusting the screw 25, and a locking nut 27 may be mounted on the threaded portion of the screw adjacent the part 8 of the supporting member to secure the screw in adjusted positions. It will be apparent that both arms of the truck

frame are pivotally connected with separated parts of the frame in such a manner that the main frame may tilt in various directions with relation to the truck frame, this tilting movement being resisted and controlled by the cushioning element 23. It will be noted that the pivotal connections between the arms 16 and 21 and the main frame are so arranged with relation one to the other as to permit of the free movement of the frame simultaneously about both pivotal connections. The stresses which are imposed upon the skate are transmitted directly from the arms of the truck frame to parts of the main frame which are of such a character and so arranged as to provide ample strength and rigidity and thus prevent any distortion or other injury of the main frame, the truck frame itself being of such a strong rigid character that it is not liable to injury in the normal operation of the skate.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a roller skate, front and rear trucks each including a frame having a roller supporting portion, an arm extending inwardly from said roller supporting portion and an arm extending upwardly and outwardly from said roller supporting portion, a frame bar of strong rigid construction throughout its length, extending lengthwise of said skate and having at its ends downwardly extending parts rigid therewith and pivotally connected with the upwardly and outwardly extending arms of the respective truck frames on axes spaced a substantial distance below the longitudinal portion of said bar, supporting members rigidly secured to said bar and spaced inwardly from said downwardly extending parts of said bar, each supporting member having in its upper portion a longitudinal groove in which said frame bar is rigidly secured, means including a cushioned element for pivotally and yieldably connecting said inwardly extending arms with the respective supporting members, and foot supporting means rigidly connected with said bar.

2. In a roller skate, front and rear trucks each including a frame having a roller supporting portion, an arm extending inwardly from said roller supporting portion and an arm extending upwardly and outwardly from said roller supporting portion, a frame bar of strong rigid construction throughout its length extending lengthwise of said skate and having at its ends downwardly extending parts rigid therewith and pivotally connected with the upwardly and outwardly extending arms of the respective truck frames on axes spaced a substantial distance below the longitudinal portion of said bar, supporting members rigidly secured to said bar and spaced inwardly from said downwardly extending parts of said bar, each supporting member having in its upper surface a longitudinal groove in which said bar is rigidly secured with its upper surface substantially flush with the upper surfaces of said supporting members, said supporting members having means for securing a foot supporting member thereto, and means including a cushioning element for pivotally and yieldably

connecting said inwardly extending arms with said supporting members.

3. In a roller skate, a main frame comprising a single bar extending for substantially the full length of the skate and of a strong rigid construction throughout its length, said bar having its end portions turned downwardly and extending a substantial distance below the longitudinal part of said bar, each downwardly extending part of said bar having a substantially round lower end forming a bearing member, front and rear trucks each comprising rollers and a truck frame supported by said rollers for movement about an axis transverse to said bar, each truck frame having an inwardly extending arm and an upwardly and outwardly extending arm provided at its upper end with an upwardly facing socket having a hardened concave bearing surface to receive the lower end of the adjacent downturned part of said bar, thus establishing universal pivotal connections between said bar and the respective truck frames at points spaced from said bar, means interposed between said bar and the inwardly extending arms of the respective truck frames to yieldably resist the relative movement of said bar and said truck frames about said pivotal connections, and foot supporting means rigidly secured to said main frame.

4. In a roller skate, a relatively narrow main frame member extending centrally of the skate for substantially the full length thereof and of strong rigid construction throughout its length, said frame member having at each end thereof a part rigid therewith and extending downwardly therefrom a substantial distance, front and rear trucks each comprising rollers and a truck frame supported by said rollers for movement about an axis transverse to said main frame member, each truck frame having an inwardly extending arm and an upwardly and outwardly extending arm, the upwardly and outwardly extending arm of

each truck frame and the adjacent downwardly extending part of said main frame member being pivotally connected one with the other for relative movement about axes extending both transversely to and lengthwise of said main frame member, and means interposed between said main frame member and the inwardly extending arms of the respective truck frames to yieldably resist the relative movement of said frames about either of said axes, and foot supporting means rigidly secured to said main frame member.

5. In a roller skate, a main frame of strong rigid construction throughout its length and having at each end a part rigid therewith extending downwardly a substantial distance below the longitudinal portion of said main frame, each of said parts being provided at its lower end with a hardened substantially semi-spherical bearing surface, front and rear trucks each comprising rollers and a truck frame supported by said rollers for movement about an axis transverse to said main frame, each truck frame having an inwardly extending arm and an upwardly and outwardly extending arm, each upwardly and outwardly extending arm having near its upper end an upwardly facing socket provided with a hardened substantially semi-spherical bearing surface cooperating with the bearing surface of the adjacent downwardly extending part of said main frame to connect said truck frame and said main frame for relative movement about axes extending respectively transversely to and lengthwise of said main frame and spaced from said main frame, means interposed between said main frame and the inwardly extending arm of each truck frame to yieldably resist the relative movement of said frames about either of said axes, and foot supporting means rigidly secured to said main frame.
